CLAIM

The ornamental design for a "portion of a bottle," as shown and described.

DESCRIPTION

FIG. 1 is a perspective view showing a first embodiment of a portion of a bottle, with the bottle shaded to indicate that it is opaque showing our new design;

FIG. 2 is a front elevation view thereof;

FIG. 3 is a left side elevation view thereof, the right side elevation view being a mirror image thereof;

FIG. 4 is a rear elevation view thereof;

FIG. 5 is a top plan view thereof; and,

FIG. 6 is a perspective view of a second embodiment of a portion of a bottle, that is identical to the first embodiment of a portion of a bottle, except that the bottle is shaded to indicate that it is a translucent surface.

The broken lines showing the top and bottom portions of a bottle appearing in FIGS. 1–6 are for the purpose of illustration only, and form no part of the claimed design.
